UNITED STATES PATENT OFFICE

163,109

SILVERWARE CHEST

Seward W. Flynn, Oneida, N. Y., assignor to Oneida Ltd., Oneida, N. Y., a corporation of
New York

Application January 19, 1949, Serial No. 317

Term of patent 14 years

(Cl. D58—12.6)

To all whom it may concern:

Be it known that I, Seward W. Flynn, a citizen of the United States, residing at Oneida, county of Madison, and State of New York, have invented a new, original, and ornamental Design for a Silverware Chest, of which the following is a specification, reference being had to the accompanying drawing, forming a part thereof, in which:

The drawing is shaded to show contrasting appearance and transparency.

I claim:

The ornamental design for a silverware chest, substantially as shown and described.

SEWARD W. FLYNN,
